MAGNETIC TAPE TRANSPORT

Darrell S. Staley, Santa Clara, Calif., assignor to Ampex
Corporation, Redwood City, Calif.

Filed Jan. 2, 1974, Ser. No. 419,904

Term of patent 7 years

Int. Cl. D14—02

U.S. Cl. D26—5 C

FIG. 1

FIG. 2

FIG. 1 is a front perspective view of a magnetic tape transport, showing my new design; and

FIG. 2 is a rear elevational view thereof shown on a reduced scale.

The left sides of the upper and lower sections of the magnetic tape transport are substantially plain and unornamented.

I claim:

The ornamental design for a magnetic tape transport, substantially as shown and described.
